UNITED STATES PATENT OFFICE

HARRY H. FLEER, OF QUINCY, ILLINOIS, ASSIGNOR TO ORBON STOVE CO., OF BELLEVILLE, ILLINOIS, A CORPORATION OF DELAWARE

DESIGN FOR A STOVE

Application filed August 25, 1930. Serial No. 36,756. Term of patent 7 years.

To all whom it may concern:

Be it known that I, HARRY H. FLEER, a citizen of the United States, residing at Quincy, county of Adams, and State of Illinois, have invented a new, original, and ornamental Design for Stove, substantially as shown in the accompanying drawing.

The drawing is a perspective view showing my new design.

The sides of the design opposite those shown in the drawing are plain or conventional in appearance.

I claim:

The ornamental design for a stove, substantially as shown and described.

HARRY H. FLEER.
